COLLAPSIBLE TUBE

William F. Schmalz, Rockville, Conn., assignor
to Colt's Patent Fire Arms Manufacturing Co.,
Hartford, Conn., a corporation of Connecticut

Application June 20, 1932. Serial No. 618,344

4 Claims. (CL 221—60)

In the packaging and distribution of toilet, cosmetic, medicinal and other preparations which are put up in collapsible tubes, considerable difficulty and large losses are incurred by reason 5 of the loosening of the threaded caps which are supposed to keep the mouths of the tubes closed.

The caps are ordinarily assembled with the tubes before the tubes are filled, and the tubes are then filled through the ends opposite the 10 caps, these ends being subsequently folded and crimped to effect sealing. The tubes are filled rapidly and in large quantities, ordinarily by means of automatic machines. If by reason of vibration or otherwise some of the caps have become loosened or detached prior to the filling 15 operation, a loss of the material or preparation will occur by reason of the discharge thereof through the mouths of the tubes during the process of filling. This involves not only the loss 20 of the said material or preparation, but also results in a defective package which has to be separated from the others and either thrown away or handled separately.

It also frequently happens that loosening or 25 detachment of the cap occurs subsequently to filling, as for instance during handling and shipment. This results in a leakage of the contents which not only renders that particular package defective, but may also render defective all of the 30 packages in the box or carton in which they are shipped. Nearly all manufacturers of preparations put up in tubes suffer large financial losses due to the return to them of packages that have 35 become defective because of loosened caps.

The principal object of the present invention is to provide a collapsible tube package and an apparatus for making the same, which substantially, if not completely, eliminates the difficulties 40 and handicaps that have been heretofore experienced by reason of loosened and detached caps.

In the accompanying drawing I have illustrated one form of collapsible tube incorporating the invention, and I have illustrated more or 45 less diagrammatically an apparatus which may be used for making tubes embodying the invention. It will be understood, however, that the drawing is intended for illustrative purposes only and is not to be construed as defining or limiting the 50 scope of the invention, the claims forming a part of this specification being relied upon for that purpose.

Of the drawing:

Fig. 1 is a plan view of a collapsible tube incorporating the invention.

Fig. 2 is a fragmentary side view of the upper part of the tube shown in Fig. 1.

Fig. 3 is an enlarged vertical sectional view of the tube shown in Figs. 1 and 2 and also showing a threaded cap in place on the tube. This view 60 is taken along the line 3—3 of Fig. 4.

Fig. 4 is a horizontal sectional view taken along the line 4—4 of Fig. 3.

Fig. 5 is a vertical sectional view showing somewhat diagrammatically an apparatus for making 65 the tube as shown in Figs. 1 to 4.

Fig. 6 is a fragmentary horizontal sectional view taken along the line 6—6 of Fig. 5.

Referring particularly to Figs. 1 and 2 of the drawing, 1 represents as an entirety a collapsible 70 tube embodying the invention. This tube is provided with a shoulder 2 and a neck 3, as is customary in tubes of this general class. The tube is provided with an aperture or throat 4 by means of which the contents can be discharged in the 75 usual way. The neck 3 is provided adjacent its outer end with screw threads as indicated at 5 and it is provided adjacent its inner or shoulder end with an unthreaded portion 6, the diameter of this unthreaded portion being approximately the 80 same as the outside diameter of the threads 5. In describing the portion 6 as being unthreaded I merely mean that the said threads 5 terminate above the said portion 6 and do not extend into it.

Formed on the unthreaded portion 6 of the 85 neck are outward projections 7, 7 adapted to frictionally engage an unthreaded cylindrical surface on a closure cap to resist rotative movement of the cap. The number of the said projections 7, 7 may be varied, but by way of illustration I have 90 shown four such projections uniformly spaced.

In Figs. 3 and 4 I have shown the collapsible tube in section on a somewhat larger scale, and I have also shown a threaded closure cap 8. The cap 8 is provided with threads adapted to engage 95 the threads 5 on the neck of the tube, and it is also provided below the threads with an internal cylindrical surface 9. The diameter of the surface 9 bears such a relation to the projections 7, 7 on the tube that the said projections have 100 firm frictional engagement with the said surface when the cap is fully engaged with the tube as shown in Fig. 3. Preferably the projections 7, 7 are of such size that a circle through their outer edges would be of slightly greater diameter than the diameter of the surface 9 on the cap. The result is that the cap has to be forced into position, the metal of the projections 7, 7 being 105 slightly deformed by the cap. This definitely assures a firm frictional engagement between the 110

projections and the said surface 9, and this frictional engagement serves to prevent any accidental rotative movement of the cap relatively to the tube such as might otherwise occur by reason of vibration and the like.

It will be understood that with a tube incorporating the invention the cap is screwed into place in the usual way, the only difference being that more force must be applied by reason of the engagement of the projections 7, 7 with the surface 9, 9 of the cap. When the cap has been screwed into its final closed position the before-mentioned frictional engagement is such as to resist any tendency toward unscrewing because of vibration and the like. The cap can be unscrewed only by the application of considerable force and this assures that the package with its contents shall reach the ultimate consumer with the cap still in its proper completely closed position. Even after the cap has been removed and replaced by the user it is still quite firmly held, and this feature is of considerable advantage to the user as it prevents any possible leakage of the contents of the tube even when packed in a suit case or otherwise for travelling.

Referring particularly to Figs. 5 and 6, 10 represents a female die member having a recess 11 therein shaped to determine the exterior contour of the desired tube. 12 represents the male die member which is shaped to determine the interior contour of the tube. The said die member 12 is adapted in accordance with usual practice to engage a metallic blank in the aperture of the female member and to press and extrude the metal of the said blank to form the desired tube. The tube as initially formed has a film of metal closing the throat 4, and this may be removed in the usual way. The neck is threaded in accordance with usual practice.

In accordance with the invention the recess 11 in the female member 10 is provided with a plurality of notches 13, 13 which are so shaped and positioned as to form a plurality of outward projections 7, 7 on the neck 3 of the tube adjacent the shoulder 2 thereof. These projections are formed simultaneously with the other parts of the tube when pressure is applied by the die member 12.

It will be apparent that with the die member 10 formed as shown, the projections 7, 7 of the tube can be formed without any additional cost. It will also be apparent that no additional cost

is involved in adapting the cap 8 for use as a part of a package embodying the invention, as it is only necessary to provide the said cap with the aforesaid surface 9. I have therefore, without any additional cost, provided a collapsible tube package in which the cap is effectively held in place on the tube, thus eliminating the various difficulties and expenses that have heretofore been due to loosening of the caps.

What I claim is:

1. A collapsible tube having the neck thereof exteriorly threaded adjacent its outer end and unthreaded adjacent its inner or shoulder end and having on the said unthreaded portion of the neck at least one outward projection adapted to engage an inner unthreaded cylindrical surface of a closure cap provided with threads engageable with threads on the neck, the said projection thus serving to frictionally hold the cap and prevent accidental loosening thereof.

2. The combination of a collapsible tube having the neck thereof exteriorly threaded adjacent its outer end and unthreaded adjacent its inner or shoulder end and having on the said unthreaded portion of the neck at least one outward projection, and a closure cap having internal threads adapted to engage the threads on the neck of the tube and having below the threads an internal cylindrical surface adapted to engage and be frictionally held by the said projection on the neck.

3. A collapsible tube having the neck thereof exteriorly threaded adjacent its outer end and unthreaded adjacent its inner or shoulder end and having on the said unthreaded portion of the neck a plurality of outward projections adapted to engage an inner unthreaded cylindrical surface of a closure cap provided with threads engageable with the threads on the neck, the said projections thus serving to frictionally hold the cap and prevent accidental loosening thereof.

4. The combination of a collapsible tube having the neck thereof exteriorly threaded adjacent its outer end and unthreaded adjacent its inner or shoulder end and having on the said unthreaded portion of the neck a plurality of outward projections, and a closure cap having internal threads adapted to engage the threads on the neck of the tube and having below the threads an internal cylindrical surface adapted to engage and be frictionally held by the said projections on the neck.

WILLIAM F. SCHMALZ.
